3 Claims. (Cl. 125—11)

This invention relates to automatic re-dressing or re-truing mechanism for a grinding wheel, and more particularly to a dressing unit and a remotely positionable power and control unit therefor, both of which can readily be incorporated in existing grinding machines.

In the past, the dressing or trueing tool was mounted on suitable compound slide rests so that it could be manipulated across the face of the wheel by manually controlled devices. This involved the grinding machine operator's shutting down the workpiece feeding apparatus, usually walking around the entire grinder to have access to the dressing tool and its controls, operating the dressing tool by means of its controls until the wheel face was satisfactorily redressed, and then coming back around the grinder and starting up the workpiece feeding apparatus and letting it run until a certain number of workpieces had been treated by the wheel, at which time the wheel again needed dressing and the entire procedure was started over. Aside from being inefficient, this process resulted in inaccurate dressing. The worker who controlled the dressing tool had to tell by ear and by feel at what speed the tool had to be moved across the face of the wheel to obtain the particular wheel surface needed for the type of workpiece being treated. The exact surface needed could not be obtained by this hit-and-miss method every time, which resulted in variations in the quality of the treated workpieces.

Machines for automatically moving the dressing tool have been proposed, but they are not entirely satisfactory for several reasons: they are expensive; when highly accurate they involve a great deal of controlling mechanism and are thus complicated as well as cumbersome; and, when made simple and compact, they can not consistently reproduce a particular required wheel surface with any accuracy.

Accordingly, it is an object of the present invention to provide an automatic dressing attachment for a grinder that is both compact and highly accurate and is, due to its simplicity, relatively inexpensive.

Another object is to provide an automatic dressing unit for a grinder that can readily be incorporated on many existing grinders to replace the previous mechanisms, whereby dressing operations can be improved without the purchase of an entire new grinder with built-in dressing apparatus.

Another object is to provide an automatic dressing unit in which the mechanism for moving the dressing tool can be mounted on most grinders and the power and control unit for this mechanism can be positioned remotely so as to fit into any available space.

A further object is to provide a power and control unit for dressing apparatus that can easily be interconnected with the controls for the workpiece feeding assembly in order to lose a minimum amount of time between the end of the workpiece feeding operation and the beginning of the dressing operation and, conversely, to start the workpiece feeding operation the instant the dressing operation stops.

A still further object of this invention is to provide controls for a dressing apparatus that will insure an extremely accurate dressing operation time after time, by precisely controlling both the speed and the direction of the dressing tool across the face of the wheel.

Further objects and advantages of the present invention will be apparent from the following detailed descrip-

2

tion, with reference to the accompanying drawings in which like reference characters refer to the same parts throughout the several views, and in which:

FIGURE 10 is a view showing in schematic fashion the control system of this invention.

The disclosed embodiment of this invention comprises a wheel dressing apparatus 10 mounted on a conventional support 12 which also supports a grinding wheel W, a workpiece feeding mechanism 199 and control units 200, 200' therefor, respectively, see FIGURE 1. A slide base 14 is adjustably mounted on an inclined face 16 of the support 12 and locked in position thereon by suitable bolts 18. The inclined face 16 is at such an angle that the dressing tool D—which in this case is a diamond cutting tool—will be movable toward and away from the wheel along a radial line A.

The dressing unit 10 is constructed to move the dressing tool D toward and away from the peripheral or working face WF of the grinding wheel W along the radial line A illustrated in FIGURE 1, and also back and forth across the working face WF of the wheel (from left to right and return as seen in FIGURE 2). In addition, the dressing tool D is advanced a small controlled distance toward the wheel along the radial line A prior to each dressing traverse of the tool across the working face of the wheel.

Back and forth movement of the tool across the working face is guided by means of a slide bar 20 integral with adjustable slide base 14 having an undercut dovetail 22 along one side. Slidable along slide bar 20 is a first carriage 24 of a compound slide rest having a slide groove 26 along its under surface which mates with slide bar 20 on the slide base. The first carriage 24 is slidable back and forth along the slide base by means of a hydraulic motor 28 comprising a conventional cylinder 30 adjustably secured to the slide base 14, as by locking screws 32, and containing a piston 34 secured to a piston rod 36 which is positively fastened at its outer end to the first carriage 24 by nut 38. Two hydraulic fluid connections 40 and 42 at either end of cylinder 30 provide access for oil for reciprocating the piston within the cylinder.

Movement of the dressing tool D toward and away from the working face of the wheel is accomplished by means of a second carriage 44 slideable, by means of dovetail ways 46, on the first carriage and at right angles to the direction of sliding movement of the first carriage. Suitable lubricating ports, not shown, allow easy back and forth sliding movement of the first carriage 24, and

easy to and fro movement of the second carriage 44 on top of the first carriage, thus providing a double or compound sliding action capable of moving the dressing tool D in any direction within a plane parallel to the sliding surface of slide base 14. The second carriage 44 is moved toward and from the wheel face on top of the first carriage by means of a second hydraulic motor 48 comprising a cylinder 50 (see FIGURE 6), a piston 52 and a piston rod 54 terminating in an abutment portion 56 secured to the first carriage 24 by means of a housing 58 containing an abutting surface 60. The cylinder 50 is secured to a block 62 by bolts 62, and block 62 is in turn locked to the second carriage 44 by means of a dovetail cut out 66 which fits over the slide member 46 of the second carriage and is clamped thereto by a gib 68 and a clamping screw 70, as seen in FIGURE 7. Hydraulic fluid is admitted to cylinder 50 by connections 72 and 74. Thus as fluid motor 48 is extended by oil pressure through connection 72, the second carriage 44 to which cylinder 50 is secured is drawn back on the dovetail ways 46, in relation to the first carriage 24 against which piston rod 54 abuts.

As the first carriage moves the dressing tool across the working face of the wheel, the dressing tool is prevented from sliding radially toward the wheel on ways 46 by means of a guide bar 76 and a guide point 78. Guide bar 76 is adjustably secured by means of a clamping block 80 and bolts 82 to the slide base 14. Guide bar 76 has a face BF along which a sharpened edge P of guide point 78 rides; this face BF acts as a cam bar and has a contour machined thereon which is the same contour desired to be obtained on the working face WF of the grinding wheel during the dressing operation. The guide point 78 is secured to the second carriage 44 by being inserted in a suitable bore 84 and held there by a set screw 86. Thus as the first carriage 24 is moved by motor 28 across the face WF of the wheel, the dressing tool D is allowed to approach the wheel no closer than is allowed by the second carriage as it slides on ways 46 and as its guide point P follows the face BF of the guide bar secured to the slide base. The point of edge P of the guide point 78 is approximately the same size as the diamond cutting or dressing tool so that the dressing tool will very accurately reproduce on the wheel's working face the same contour BF that has been machined on the guide bar 76.

This invention also provides apparatus for advancing the dressing tool radially toward the wheel a small distance prior to the dressing movement of the tool across the working face of the wheel. This distance corresponds to the amount of material to be removed from the wheel by the tool during the dressing traverse, not allowing for the very small reduction in wheel diameter from wear caused by the workpieces previously ground. This apparatus for incrementally advancing the dressing tool D in relation to the second carriage 44 is best seen by referring to FIGURES 1, 3, 4 and 5. Dressing tool D is mounted (usually by means of a diamond rotating mechanism, not shown) on a slide rod or tool holder 88 slideable within a sleeve 90, which in turn is adjustably clamped within a surrounding housing on second carriage 44 by any suitable clamping means, not shown. Tool holder 88 is thus movable radially toward the wheel in relation to sleeve 90 which is, in effect, a portion of the second carriage 44. This movement is accomplished by a screw connection for finely controlling the incremental advance of the dressing tool.

This screw connection comprises, as best seen in FIGURE 3, a tapped bore 92 in tool holder 88, and a rotatable member 94 having a threaded portion 96 mating with threads 92, and being journaled in bearing 98 within a housing 100. Housing 100 is affixed to sleeve 90 (and thus to the second carriage 44) by slotted portion 102 which is tightly secured by bolts 104. Member 94 is rotated within the housing 100 by a worm wheel 106 keyed thereon. Worm wheel 106 is rotated by a worm

gear 108 keyed on a shaft 110 which is journaled at 112 in housing 100. Shaft 110 may be turned to advance the dressing tool (via worm gear 108, worm wheel 106, screw connection 96, 92, and tool holder 88) toward the grinding wheel by means of a hand crank 114.

However, automatic means is provided for turning shaft 110 so that errors implicit in manual operation will be eliminated during production line use of the invention. This automatic means consists of a ratchet unit 10 within cover 116 which is removable from the housing 100 simply by removing bolt 118 through the hand crank which holds the entire ratchet unit within cover 116 tightly on conical wedge taper portion 120 of shaft 110. When bolt 118 is removed, hand crank 114 can be removed from the square end 122 of a hollow ratchet shaft 124 which contains a wedge taper 126 compatible with the taper 120 on shaft 110. Also keyed at 128 on ratchet shaft 124 is a circumferential dial member 130 which indicates the amount of turn of shaft 110 in relation to markings (not shown) on face 132 of cover 116. When the unit is assembled, tightening bolt 118 renders crank 114, ratchet shaft 124, and worm shaft 110 a unitary structure, as seen in FIGURE 5. This unitary structure is automatically rotatable by a pawl 134 which will rotate a ratchet 136 on ratchet shaft 124 in one direction only. Pawl 134 is oscillated around rotary ratchet 136 by a member 138 which surrounds ratchet shaft 124 and is rotatably separated therefrom by annular bronze bearing sleeve 140.

Member 138 has two ears 142, 144 to which the pawl 134 and its spring 146 for urging the pawl into engagement with the ratchet are attached, respectively. As member 138 and its two ears 142, 144 are rotated clockwise (FIGURE 4), pawl 134 will engage the teeth of ratchet 136 and rotate it and the ratchet shaft 124 clockwise; this motion will, due to wedge taper connection 120, 126 (FIGURE 5) thus rotate worm gear shaft 110. Return oscillation of member 138 will not rotate worm gear shaft 110 back in the opposite direction because the pawl 134 will ride over the inclined side of the ratchet teeth against the urging of spring 146, as is well known.

Member 138 is oscillated around a certain distance, and then back, once prior to each traverse of the dressing tool across the working face of the grinding wheel by a rectilinearly reciprocable hydraulic motor 150. Best viewed in FIGURE 4, member 138 has a third radially extending ear 148 by which the member is oscillated as piston 152 of motor 150 reciprocates within cylinder 154. Elongated piston 152 has, intermediate its ends, a cut out portion 156 for receiving the ear 148. Within the cut out portion 156 a pivot pin 158 secured to the piston 152 rides in a slot 160 in the end of ear 148. As piston 152 reciprocates by means of hydraulic fluid admitted to the cylinder through connections 162, 164, member 138 will oscillate pawl 134 by the interaction of the pivot pin 158 in the slot 160 in the end of ear 148. In order to get a particular oscillation of member 138 and thus an extremely finely controlled rotation of worm gear shaft 110, a manually adjustable limit stop 166 is utilized to limit the stroke of piston 152 within its cylinder 154.

Means enabling worm gear shaft 110 to be rotated backwards by the hand crank against the braking action of the pawl and ratchet mechanism in emergency situations is also provided. When piston 152 is in its rest position it abuts a stop screw 170 at the bottom end of cylinder 154. When this condition obtains, ear 148 oscillates member 138 around counterclockwise (FIGURE 4) to a point where edge 172 of pawl 134 engages a fixed pin 174 and the pawl is thus swung out of engagement with the teeth of the ratchet 136. In this condition the ratchet is ineffective and the worm gear shaft 110 can be rotated in either direction by the hand crank. As piston 152 is elevated by fluid admitted through connection 162, ear 148 will oscillate member 138 clockwise and pawl edge

172 will be moved away from pin 174 allowing the pawl spring 146 to immediately urge the pawl into engagement with the ratchet teeth and turn the ratchet shaft as the piston 152 continues its upward stroke. In FIGURE 5, the position shown is just after the piston has left its rest position, with the pawl just moving into engagement with the ratchet teeth after leaving pin 174.

Thus one up-and-down reciprocation of hydraulic motor 150 will rotate worm gear shaft 110 a pre-set number of degrees in one direction. And rotation of worm gear 108 will, through worm wheel 106 and screw connection 96, 92 advance dressing tool holder 88 an increment equivalent to the amount of material the diamond tool is intended to remove from the working face of the grinding wheel on its subsequent traverse. This traverse is effected by motor 28 moving the first carriage 24 parallel to the wheel face while the second carriage 44 and its tool holder 88 ride radially toward and from the wheel in response to the guide point P on the second carriage riding along guide bar BF fixed to the grinder support. After this traverse is completed and the working face of the wheel is satisfactorily dressed, motor 48 draws the second carriage and its associated tool holder radially back along ways 46 away from the vicinity of the grinding wheel and holds it there while motor 28 moves the first carriage 24 back (to the left in FIGURE 2) to its rest position. During this return motion the guide point P is back away from guide bar BF. The motor 48 returns the second carriage to the vicinity of the grinding wheel until guide point P again rests on guide bar BF. At this point the three motors are in their rest positions and the automatic dressing apparatus is in condition to wait while workpieces are being fed to and treated by the grinding wheel at the other end of the grinding machine. When a certain number of workpieces have been treated, the wheel again needs dressing, and the above operation is repeated.

The three fluid motors which cause the above described movements are powered and controlled from a remotely positionable unit 200 which may be located at any convenient place on or about the grinding machine 12, such as on a bench 202. This unit is tied in with and controlled by a similar unit 200' located at the opposite end of the machine for powering and controlling the workpiece feeding apparatus 199. These two power and control units 200, 200' are cam-driven liquid column type motion transfer devices, and they are illustrated schematically in FIGURE 10. The unit 200' for powering and controlling the workpiece feed machine 199 is only fragmentally shown in the lower right hand corner of the figure, and the parts, wherein they are similar, are identified by the same reference character with the addition of a prime mark as the parts in the unit 200 for powering and controlling the dressing mechanism 10.

The cam-driven liquid column type motion transfer unit 200 is shown in the upper portion of FIGURE 10. It consists simply of a prime mover 204 driving a belt 205 which rotates a worm gear shaft 208. Shaft 208 runs through a hydraulic clutch 210 and has mounted thereon worm gear 212 for rotating a cam shaft 214 by means of a worm wheel 216. Fluid for the hydraulic clutch 210 is pumped from reservoir R by a pump P and through a spring loaded, solenoid actuated valve V. When the valve is in its spring urged rest position (designated by the unhatched rectangle with the single head flow-direction arrow), fluid will be allowed to flow back to the reservoir through line 218 from clutch 210, thus disengaging the clutch and stopping cam shaft 214. When the valve V is in its solenoid actuated position (designated by the cross-hatched rectangle with the double head flow direction arrow), fluid will be allowed to surge from the pump P to the clutch 210, thus engaging the clutch and driving cam shaft 214.

Cam driven liquid column type motion transfer unit 200' for powering and controlling the feed mechanism

199 contains similar structure with the addition of a three way valve 220 and a hydraulic brake 222 for worm shaft 208'. When the valve 220 is in its spring urged rest position (designated by the unhatched rectangle) fluid will flow from the reservoir R' through pump P' and to the hydraulic brake 222 (double head flow arrow), and will drain back to the reservoir from clutch 210' (single head flow arrow), thus holding cam shaft 214' against rotation. When the valve 220 is in its solenoid actuated position (designated by the cross-hatched rectangle) fluid will drain from the brake 222 back through line 224 to the reservoir R' (single head flow arrow), and will also pass to clutch 210' (double head arrow), thus releasing the brake and engaging the clutch simultaneously and enabling shaft 214' to rotate in response to prime mover 204'. The addition of the brake in unit 200' is to insure stopping of cam shaft 214' at a precise rotational point so that the feed mechanism 199 which it controls will be stopped exactly at the end of a feed cycle.

While such precision is not required in the dressing apparatus 10 of the preferred embodiment, such precision could readily be obtained by the inclusion of a similar brake and three-way valve in the power and control unit 200 for the dresser. In the present embodiment, the cam shaft 214 in unit 200 will coast only a small amount after the clutch 210 is disengaged, and well within feasible design latitude for such a unit without requiring the use of a brake.

Cam shaft 214 has three fluid motor operating cams thereon, one for powering and controlling each of the motors of the automatic dressing unit 10. Cam 250 controls motor 150 for incrementally advancing the tool holder; cam 228 controls motor 28 for traversing the dressing tool across the face of the wheel; and cam 248 controls motor 48 for withdrawing the second carriage and its tool holder radially from the vicinity of the grinding wheel.

Each cam has riding on its peripheral working face a cam follower 230 which is linked at 232 to a piston 234. Each cam, follower, link and piston is thus a pulsator capable of transmitting motion imparted by rises and falls on the cam's surface. The piston of each pulsator reciprocates within a fixed cylinder 236 and forms therewith a fluid chamber 238 containing oil under low, super-atmospheric pressure. Attached to each cylinder and communicating with the chamber is flexible piping, such as 162, also containing oil under low pressure. (Since the pulsator unit and piping for each cam are the same structurally, a description of the one for cam 250 will suffice to describe all.) As the follower 230 follows a rise on cam 250, the pulsator piston 234 will reduce the size of the chamber 238 and thus transmit motion through liquid column 162 to fluid motor 150, where the motion is received by and imparted to piston 152.

The steeper the rise on the cam, the faster the movement of the motor piston which receives such motion. The ratio between the face areas of the pulsator piston (transmitter) and the motor piston (receiver) will further tend to govern the speed with which the motor piston moves as well as the length of its stroke. Obviously, by careful design of the cams and careful planning of the areas of the two pistons, a very precise powering and controlling of the fluid motors is obtained.

The cam actuated liquid column type motion transfer units of this invention also incorporate means for returning the pistons to their rest positions. The oil connection 164 at the other end of fluid motor 150, for instance, runs to a supply of oil under high pressure, RO. This preferably is a single air loaded accumulator connected to supply return oil (RO) to all of the motors of the dressing apparatus 10. As the piston 152 of motor 150 is return toward its rest position by the pressure of the return oil through connection 164, the liquid column 162, 238 acts through the pulsator to urge the cam follower 230 continually against the falling surface of cam 250. The cam

on the return stroke serves only to control the speed with which motor piston 152 returns toward its rest position under pressure of the return oil from RO.

The head 246 of each pulsator contains a replenishing check valve 240 and a spring loaded relief valve 242. All the replenishing and relief valves are connected to a common oil source or reservoir 244 formed in the housing of unit 200. Check valves 240 allow flow from the reservoir 244 to the chamber 238, while relief valves 242 allow flow oppositely when the cylinder pressure exceeds a certain value. Thus each of the pair of valves 240, 242 may be referred to as a balancing valve and serves to balance the volume of fluid in each of the liquid columns. As a pulsator transmits more motion (fluid displacement) to a motor piston than the piston's limit stops permit, oil pressure will build up at the end of a power stroke and overcome the pre-set force of the relief valve's spring and excess oil will be diverted to the reservoir 244. As the cam then passes its peak and presents a falling face, the pressure of the return oil from RO will cause the motor piston, via the liquid column and pulsator, to keep the follower urged against the cam. When the motor piston reaches its limit stop in the rest position, the follower continues to be urged against the cam by the falling pressure in the liquid column. As the cam face falls to near its base circle, the motor stroke is completed and the pressure in the liquid column will fall to near the low, super-atmospheric pressure of the reservoir 244. Because oil had been lost from the liquid column through the relief valve during the cam's rising portion and the pressure in the liquid column will fall below the reservoir pressure, check valve 240 will replenish the liquid column and keep it at reservoir pressure thus still urging the follower against the cam at all times. And as the cam starts to present a rising face as it begins its next revolution, so the process would be repeated.

Thus a cam actuated liquid column type motion transfer unit 200 is provided which has its own balancing valves 246 for relieving excessive pressures and later replenishing oil to the liquid columns. Further, because of the flexible piping interconnecting the power and control unit and the motors which the unit controls, the unit can be located in any convenient place on or adjacent the grinding machine. Thus an arrangement combining the flexibility of fluid motors and the precision and power of cam control is provided in which simplicity and dependability make the arrangement adaptable to most grinding machines.

The units 200 and 200' for powering and controlling the dressing apparatus 10 and the feeding mechanism 199, respectively, are interconnected by means of a commercial electrical counting device 300 for beginning the dressing cycle immediately upon completion of the feeding of a pre-determined number of workpieces, and to stop the dresser and commence work feeding the instant the dressing operation is complete. The counter 300 contains a conventional ratchet actuating solenoid, or count coil, 302 and a clutch reset solenoid, or clutch coil, 304. In addition, the counter contains a switch for making contact between connections 306 while breaking contact between connections 308 in one position, and vice-versa in the other position. Current for powering the circuitry of FIGURE 10 is provided by lines 310.

When the unit 200' is operating and workpieces are being successively fed to the wheel by mechanism 199, a cam 312 closes contacts 314 once on each revolution of cam shaft 214'. On each momentary closing of contacts 314, current from power lines 310 is pulsed through count coil 302. During this time contacts 308 are open and 306 are closed, providing power for the solenoid on valve 220 and engaging hydraulic clutch 210' and releasing brake 222. When a preset number of revolutions of cam shaft 214' (determined by the type of workpiece, etc.) have been recorded in the counter, the counter

switch is thrown to the position shown and contacts 306 are opened and 308 closed. The instant contacts 306 are opened, the brake 222 is applied and the clutch 210' is disengaged, thus stopping cam shaft 214'.

5 Closing of contacts 308 closes solenoid actuated switch 320 for starting the prime mover 204 of the unit 200, and also actuates solenoid operated valve V to engage hydraulic clutch 210, thus permitting cam shaft 214 to be rotated by prime mover 204. Thus immediately upon the counter recording a pre-set number of workpiece feeding cycles, the workpiece feeding mechanism is idled and the dressing apparatus is actuated to begin the dressing cycle.

As the cam shaft 214 revolves, the cams 250, 228 and 248 cause the fluid motors 150, 28 and 48 of the dressing apparatus to incrementally advance the diamond, traverse it across the wheel's working face, withdraw it radially from the vicinity of the wheel and return it to its starting point in the manner previously described. Because of the nature of the cams in unit 200, this sequence can easily be changed to fit any desired sequence, and the sequence described with this preferred embodiment is merely exemplary and not exclusive.

When the fluid motors are again in their rest positions after the dressing cycle has been completed, and before cam shaft 214 has completed its revolution, a cam 322 momentarily closes contacts 324 and pulses current through the counter's clutch coil 304 which resets the counter and moves the counter's switch to break contact at 308 and make contacts 306. As current stops flowing through contacts 308, solenoid switch 320 will shut off prime mover 204 and the spring of valve V will return it to its rest position disengaging hydraulic clutch 210, thus allowing cam shaft 214 to quickly coast to a stop, and the peaked lobe of cam 322 to pass just beyond the follower. Closing of contacts 306 again starts unit 200' and the workpiece feeding operation is resumed.

Thus a completely automatic and highly accurate dressing device well adapted to the rigors of high production industrial grinding has been disclosed and, while this 40 particular embodiment constitutes a preferred mode of carrying out this invention, many other forms might be adopted within the scope of the actual invention, which is variously claimed as:

1. Controls for an automatic grinder including workpiece feeding mechanism and wheel dressing apparatus, said controls comprising two separate mechano-hydraulic motivators of the liquid column motion transfer type including cam actuated pulsators for transmitting motion through liquid columns to piston receivers in fluid 45 motors, one of said units powering and controlling said feeding mechanism exclusively and the other powering and controlling said dressing apparatus exclusively; a counting device associated with said two units; said counting device including means, operative in response to 50 means in said one unit, for stopping said one unit and starting said other unit, and further responsive to means in said other unit, for starting said one unit and stopping said other unit.

2. An automatic wheel dresser for a grinding machine 55 comprising a support and a grinding wheel mounted for rotation thereon, handling means on the support for presenting workpieces to the wheel through successive grinding cycles, a compound slide rest on the support and a wheel dressing tool mounted on the slide rest for manipulation relative to the wheel, fluid motors connected to manipulate the tool through a wheel dressing cycle, a mechano-hydraulic motivator of the rotary cam powered and controlled liquid column motion transfer type connected to operate the fluid motors to dress the 60 wheel, and control means responsive to the completion of a grinding cycle for rendering the motivator operative to power and control a dressing cycle of the tool and also for rendering it inoperative upon completion of a dressing cycle.

75 3. An automatic wheel dresser for a grinding machine

comprising a support and a grinding wheel mounted for rotation thereon, a compound slide rest on the support, a wheel dressing tool mounted on the slide rest for manipulation relative to the wheel, a plurality of shiftable piston type fluid motors each comprising a double acting expandible chamber type pulse receiver connected to manipulate the tool, a plurality of shiftable piston type pulsators each comprising a single acting expandible chamber type pulse transmitter, a plurality of liquid columns connected between the pulsators and the motors to transfer transmitter motions to the receivers in one direction, a source of pressurized fluid, means connecting the source with each fluid motor in opposition to the liquid column connection to bias the receivers counter to transmitted motions, a common liquid reservoir, overload relief and check replenishing valves interconnecting each liquid column and the reservoir to

balance the volume of liquid in each column, a plurality of rotary cams connected to operate the pulsators through a predetermined sequence of movements, and common camshaft means connected to drive the cams in unison whereby the tool is manipulated relative to the wheel through a wheel dressing cycle.
